Patented Mar. 22, 1921.

UNITED STATES PATENT OFFICE.

WALTER ROUSH, OF TOLEDO, OHIO.

SIGNAL DEVICE.

1,372,313.

Specification of Letters Patent. Patented Mar. 22, 1921.

Application filed October 29, 1920. Serial No. 420,382.

To all whom it may concern:

Be it known that I, WALTER ROUSH, a citizen of the United States, and a resident of Toledo, Lucas county, Ohio, have made 5 an Invention Appertaining to Signal Devices; and I do hereby declare the following to be a full, clear, and exact description of the invention, such as will enable others skilled in the art to which it appertains to 10 make and use the same, reference being had to the accompanying drawings, and to the characters of reference marked thereon, which form a part of this specification.

This invention relates to signal devices, 15 and particularly to those of a movable or animated nature adapted for use on automobiles or the like to attract the attention of the drivers of vehicles in the rear, or of others, to indicate that the vehicle on which 20 the signal is displayed is going to slow up or turn.

The object of my invention is the provision of a simple and improved signal device of the character described, which simulates 25 a hand and is operable to open when in use as a signal and to close when not in use.

The invention is fully described in the following specification, and while, in its 30 broader aspect, it is capable of embodiments in numerous forms, a preferred embodiment thereof is illustrated in the accompanying drawings, in which,—

Figures 1 and 2 are edge and front elevations of a device embodying the invention with the hand in closed position. Fig. 3 is a front elevation thereof with the hand in open position, and Figs. 4, 5, 6, 7 and 8 are face views of the different members of the 40 hand, with that of Fig. 6 partly broken away.

Referring to the drawings, 1 designates a holder in the nature of a hollow guide member, which in cross-section is broader in one 45 dimension than the other, and which has one end open. A set of five elongated members form the signal hand 2 of the device, which members are of thin sheet metal or other suitable material of a stiff nature and 50 are placed flatwise one on another and have their inner ends projected into the guide or holder 1 for limited longitudinal reciprocatory movements together therein and for limited relative pivotal movements.

55 The different members of the hand 2 form the thumb 3 and the first, second, third and

fourth fingers 4, 5, 6 and 7 of the hand. These members have a body or palm portion 8, 9, 10, 11 and 12, respectively, which are of the same width and of a size adapted 60 when in registering relation one over the other to fit and slide into the open guide end of the holder 1. The finger members have wrist portions 13, 14, 15, 16 and 17, which are pivotally connected at 18 to permit relative lateral pivotal movements of the members so that the fingers and thumb may be collapsed in the closed position shown in Fig. 2 or laterally spread in the 65 open signal position shown in Fig. 3. 70

The second finger member 5 has its wrist portion provided with an extension or forearm part 19, which is broader than the wrist portion and fits in the holder 1 to permit the member 5 to have longitudinal sliding movements therein but prevents lateral rocking movements thereof so that the other finger members are in reality pivoted to the member 5 for opening and closing movements relative thereto. The wrist portion 80 15 of the member 5 is narrowed or has its sides in-cut with respect to the palm and forearm portions 10 and 19 thereof to form stops 20 at the ends of the wrist portion for coaction with the stops 21 at the outer open 85 end of the holder 1 at opposite edges thereof to limit the reciprocatory movements of the hand within the holder, such stops, in the present instance, being in the form of 90 rollers.

The thumb member 3 has the sides of its wrist portion forming cam surfaces 22 and 23 which coact with the respective rollers 21 to swing the thumb member 3 laterally to the open position shown in Fig. 3, when the 95 hand is moved outwardly relative to the holder, and to swing the thumb member to its closed position with its palm portion in register with the palm portions of the other members, as shown in Fig. 2, when the hand 100 is moved to the limit of its inward position with respect to the holder. The first finger 4 is likewise formed at its wrist portion with suitable cam edges 24 and 25, which cause the finger 4 to have a slight lateral movement toward the open position of the thumb when the hand is moved outward relative to the holder, and vice versa, as is apparent. The middle finger member 5, as previously 105 stated, is intended to only have longitudinal reciprocatory movements and the side edges of its wrist portion are therefore made 110

straight and not in cam form. The third finger member 6 is intended to have reverse lateral movements to that of the member 4 and the cam edges 26 and 27 of its wrist portion are therefore formed with cam curves of reverse form to those of the member 4 so that they may coact with the rollers 21 to effect a lateral movement of the member 6 to the right when the hand is moved outward relative to the holder 6, and vice versa. The fourth or little finger member 7, has its wrist portion formed with the opposite cam edges 28 and 29, formed as shown, to adapt them to coact with the rollers 21 and cause a lateral movement of the finger member 7 to the right to full open position when the hand is moved outward and to return it to its collapsed or closed position when the hand is moved inward relative to the holder, as indicated by Figs. 3 and 2 respectively. When the hand is in its closed position with respect to the holder 1 the inner or wrist ends of the palm portions of the different members coact with the rollers 21 to prevent relative lateral pivotal movements of the members.

The reciprocatory movements of the hand are controlled by longitudinal movements of a rod 30, which is connected at one end to the inner end of the finger member 5 and projects therefrom through a guide opening 31 in the inner end of the holder 1. This rod may connect with any suitable operating means arranged in any suitable position.

35 It is evident that I have provided a simple and efficient signal device simulating a hand, which may be operated to throw the hand quickly to open or signaling position or to retract or move the same to closed inoperative position and that the relative opening and closing movements of the hand members are controlled by cam action.

I wish it understood that my invention is not limited to any specific construction, arrangement or form of the parts, as it is capable of numerous modifications and changes, without departing from the spirit of the claims.

Having thus described my invention, what 50 I claim as new, and desire to secure by Letters Patent, is,—

1. A signal device of the class described, comprising a holder forming a guide, a plurality of members simulating the thumb and finger members of a hand and pivoted together for relative lateral pivotal movement, said members being mounted at their

inner ends for reciprocatory movement in the holder, one member being guided for true longitudinal reciprocatory movements 60 by the holder and the other members having differently shaped cam portions coacting with the holder to impart predetermined relative opening movement to the members when moved outward and relative inward or 65 closing movement to the members when moved inward relative to the holder.

2. A signal device of the class described, comprising a holder forming a guide socket with internal projections at opposite sides 70 thereof, a plurality of members simulating the thumb and finger members of a hand and connected together for relative lateral pivotal movement about a common pivot, said members being mounted at their inner 75 ends for a reciprocatory movement in the holder, one member being guided for substantially true longitudinal movement by the holder and the other members having the side edges of their inner end portions 80 notched to receive the respective projections of the guide and to coöperate therewith to impart predetermined relative opening movement to the outer end portions of the members when moved outward, and vice 85 versa.

3. In a signal device of the class described, a hollow holder having an open end, a plurality of members simulating the thumb and finger members of a hand and 90 each having a thumb or finger portion, a palm portion, and a wrist portion, the members being pivoted together at their wrist portions for relative lateral opening and closing movement to place the palm portions into and out of register, the members being carried at their inner ends by the holder for longitudinal movement of their wrist portions in the holder, one member being longer than the others and guided by the 95 holder for true reciprocatory movement, and the other members having their wrist portions provided with cam edges which coact with the holder to impart positive pivotal opening movement of the members 100 when moved outward and positive closing movement to the members when moved inward relative to the holder, and means connected to the inner end of the longer member and operable to reciprocally move the 110 same.

In testimony whereof I have hereunto signed my name to this specification.

WALTER ROUSH.
